DECORATIVE ESCUTCHEON PLATE FOR A LOCK

Richard H. Arbib, New York, N. Y., and Robert S. Quandt, Levittown, Pa., assignors to Independent Lock Company, Fitchburg, Mass., a corporation of Massachusetts

Application November 4, 1954, Serial No. 32,962

Term of patent 14 years

(Cl. D50—6)

Fig. 1.

Fig. 2.

Figure 1 is a front elevational view of a decorative escutcheon plate for a lock showing our new design.

Figure 2 is a section on the line 2—2 of Figure 1.

The characteristic features of the design reside in the spheroidal, peripheral edge frame which surrounds the inwardly dished, concavely fluted and radially extended central portion.

We claim:

The ornamental design for a decorative escutcheon plate for a lock, substantially as shown and described.
